[57] CLAIM

The ornamental design for a multi-level sheet feeder, as shown.

DESCRIPTION

FIG. 1 is a front elevational view of a multi-level sheet feeder showing my new design;

FIG. 2 is a top plan view thereof;

FIG. 3 is a left-side elevational view thereof;

FIG. 4 is a right-side elevational view thereof;

FIG. 5 is a rear elevational view thereof;

FIG. 6 is a bottom plan view thereof;

FIG. 7 is a top, front, perspective view thereof, the broken lines showing a copier being environmental only and forming no part of the claimed design;

FIG. 8 is a top, front, perspective view showing a second embodiment of my design of FIGS. 1-7;

FIG. 9 is a top plan view of the second embodiment.

FIG. 1

FIG. 2

FIG. 3

FIG. 4

FIG. 5

FIG. 6

FIG. 7

FIG. 8

FIG. 9
